JOSEPH GOULDBOURN AND GEORGE HAZELTON, OF LEICESTER, ENGLAND, ASSIGNEES
TO UNITED SHOE MACHINERY CORPORATION, OF PATERSON, NEW JERSEY, A COR-
PORATION OF NEW JERSEY

COVERING BREASTS OF HEELS

Application filed January 3, 1930, Serial No. 418,372, and in Great Britain January 17, 1929.

This invention relates to methods of making shoes and is herein illustrated as applied to securing covers to the breasts of heels.

In the manufacture of shoes having wood heels, a leather cover is usually provided for the breast of the heel which in the case of Louis heels is formed as a flap cut from the sole of the shoe and secured adhesively to the breast of the heel after the otherwise covered heel has been attached to the shoe. This covering flap which forms a continuation of the sole has been secured in position by various adhesives and in accordance with various methods, none of which has been wholly satisfactory. If glue was used to attach the flap, it was customary to clamp the flap in position against the breast of the heel and owing to the slow setting of the glue, it was necessary to leave the shoe in the clamp for considerable time, thereby involving a substantial capital outlay in large numbers of clamps, delaying the progress of the work and requiring a relatively considerable space in the factory. In other cases, some form of rubber cement has been utilized and the parts, after they have become tacky, have been merely stroked and wiped down into snug contact without utilizing any clamping mechanism. This method, while avoiding the use of clamping apparatus, does not give the same assurance of a reliable and durable adhesion and the considerable sleeking and wiping involved is apt, in some cases, to mar the surface of the breast flap.

One object of the present invention is to provide an improved method of attaching breast covers by means of which a high quality of work may be performed at greater speed and at less expense.

It has been found that a high grade of work can be secured at a minimum of expense and the necessity for leaving the shoe in a clamp for a considerable length of time can be avoided if the adhesive utilized for attaching the cover to the breast of the heel is allowed to dry, and later when it is desired to secure the breast cover to the heel, is revived by the application of a solvent so that it becomes tacky without being sufficiently fluid to require a long drying period or

necessitating its retention in a clamping device for a long time. As illustratively described a coating of glue is applied preferably both to the attaching surface of the covering flap and to the breast surface of the heel at some convenient time, it may be before the parts are assembled in the shoe. When the time comes for attaching the breast cover to the heel the coating of glue is revived by the application of wet steam. The treatment thus described permits the time of clamping to be greatly reduced, say, for example, to two minutes. It is found further, especially in those cases where the covering flap is of substantial thickness, that it is necessary to stretch the sides of the flap or to mold the flap to the shape of the breast of the heel in order to avoid the tendency of the flap pressed into the hollows of the breast to spring away therefrom, if the clamping pressure is released before the adhesive is well set. This tendency is of sufficient importance in some instances to warrant the introduction of a separate molding operation. A separate molding operation may be avoided, however, if, in accordance with a feature of the invention, the outer or grain surface of the covering flap is tempered slightly, whereby the covering flap may nevertheless be firmly secured in the hollows of the heel during the brief clamping period otherwise required. As illustratively described, this novel step consists in applying the wet steam such as is utilized in softening the adhesive, directly to the face of the leather opposite to that which is to be stuck down, so as to temper it.

For the sake of convenience and of cleanliness in the handling of the adhesive, the latter may be supplied in the form of a dried coating upon the opposite sides of a carrier. Then, in accordance with the invention considered in another aspect, the dried coating on the carrier may be revived by the application of a solvent, illustratively described as steam, the carrier interposed between the flap and the heel, and the flap and carrier pressed against the breast of the heel. As illustratively described, the carrier is of thin paper somewhat larger than the heel breast.

and has one or more uncoated margins by which it may be grasped by the operator. Preferably, these marginal portions and marginal portions of the breast flap are trimmed off at the same time.

There will now be described an illustrative method of making shoes in accordance with the present invention, reference being had to the accompanying drawings, in which

10 Fig. 1 shows a shoe in which glue has been applied to the breast flap and to the breast of the heel and allowed to become dry;

Fig. 2 shows the reviving of the glue, to render it tacky, by the application of wet 15 steam;

Fig. 3 shows an alternative method of supplying adhesive for the attachment of the breast flap, a carrier sheet being utilized on which the adhesive has been allowed to dry 20 and which is softened by presentation to a jet of steam;

Fig. 4 shows such an adhesive carrier in position and the breast flap being tempered by the application of steam to its grain or 25 outer surface;

Fig. 5 illustrates the clamping of the covering flap against the heel; and

Fig. 6 shows how the marginal portion of the flap may be trimmed, removing at the 30 same time the unused margin of the adhesive carrier, if one has been used.

Our novel method will be described herein as applied to a shoe 10 in which a breast covering flap 12 has been split from the sole 14 35 and to which shoe there has been secured a wooden heel 16, the curved sides of which are covered with a thin material 18 which may be of leather, cloth, celluloid or the like. Although the method is to be described as employing glue as an adhesive, it will be understood that this is merely for the sake of illustration and that the method is equally applicable to other adhesives (of which pyroxylin cement may be taken as one example) 40 which may be allowed to dry to a non-tacky condition and then revived by the application of a suitable solvent.

In carrying out our novel method, an operator takes a shoe 10 from a rack of shoes 50 awaiting treatment and uniformly but thinly coats the split face of the breast flap 12 (including that part of the latter which is to lie on the tread under the heel), and the breast 20 of the heel 16 itself with glue, by brushing 55 it thereon or applying it in any other convenient manner. For this purpose the glue will be maintained in fluid condition in any of the usual forms of heated glue pots. He then lays the shoe aside with the flap 12 60 turned back to permit the glue to set. This will take place comparatively quickly because of the full exposure of the coated surfaces to the atmosphere and the shoe may be left in this condition for any length of time 65 until required for the next operation.

When the time comes for effecting the application of the breast flap to the breast of the heel, the operator takes the shoe and holds it as shown in Fig. 2 adjacent to a jet of wet steam 26 issuing from a valve controlled nozzle 28, turning the shoe so that the steam is played upon the coated surface 22 of the covering flap 12 and upon the coated breast surface 20 of the heel, until the said surfaces have been brought to a tacky condition. 75

It has been observed that a dried coating of glue or the like can be brought quickly and reliably to a condition of uniform stickiness over its surface by causing such a jet of wet steam to impinge thereon, and that, as a result, the adhesive is readily brought to such a condition that it will have the requisite tackiness to effect adequate bonding of the parts without danger of the adhesive squeezing out at the sides of the heel and soiling the side covering 18. This softening of the glue may be accomplished by playing the steam jet upon it for a few, say three or four, seconds. Having thus provided a film of adhesive between the surfaces to be attached, 90 the breast flap may be placed in position on the heel breast and clamped thereon, as later will be described.

Advantageously, too, the grain surface of the covering flap 12 is tempered by applying 95 a jet of steam 30 from, for example, a nozzle 32 attached to a flexible hose 34 as indicated in Fig. 4. In this way the grain surface of the flap is moistened and rendered pliable so that it may be readily pressed into the valleys 100 along the sides of the heel breast 20, it being understood that the steaming is so limited that the grain surface does not become obviously wet, the exact time employed depending upon various factors, such as the thickness of the breast flap. This tempering operation will usually precede the laying of the breast flap and the operator will stroke the latter by hand so as to lay it upon the breast 105 face free from undue folds or wrinkles. 110

Instead of applying glue directly to the breast flap and to the heel so as to provide a film of glue between the surfaces to be bonded, there may be interposed between these surfaces an adhesive carrier 40 which is somewhat similar in shape to but slightly larger than the breast of the heel. This carrier may be of paper, for example, and provided upon its opposite faces with a coating 42 of glue which has been allowed to become 120 dry. When such adhesive carriers are employed they may be prepared in advance and piled up in a stack as shown in Fig. 3 ready for removal one at a time. To facilitate handling such carriers they preferably have uncoated margins 44 which may be grasped by the operator's hand 45 in order to present the carrier to a jet of steam 26 issuing from a nozzle 28, to render the glue tacky. Usually 125 this will be done just prior to the use of the 130

carrier as the carrier is interposed between the flap 12 and the heel 16 as shown in Fig. 4. At this time the grain surface of the flap 12 may be tempered, as previously described and as shown in Fig. 4, if desired and the flap will be pressed into engagement with the breast of the heel with the carrier sheet 40 interposed, and the operator will stroke the flap to lay it on the breast face at the same time freeing it of wrinkles.

He then will take the shoe with the breast flap stuck in position and will employ any suitable sort of a clamping mechanism to press the flap firmly into position against the breast of the heel. For the sake of illustration, this is shown as accomplished by means of an apparatus like that of Letters Patent of the United States No. 1,716,655 granted June 11, 1929, upon the application of J. R. Nowack. This apparatus provides a flexible, inflated bag 50 supplied with air through a tube 52 which bag is mounted in position by means of clamps 54 upon a support 56. The shoe with the flap pressed manually into position is placed in the manner shown in Fig. 3 upon the inflated bag 50 and pressed firmly thereagainst by means of a clamping lever 58 supported upon upright rods 60 acting directly upon a protecting angle-iron 62. The shoe may be left in this position for the length of time necessary to insure a firm bonding of the heel breast covering flap. With the improved method herein described, this time is greatly reduced because of the tacky condition in which the adhesive is, at the time that the breast flap is laid, and it has been found by experience that a two-minute interval will allow the glue to set sufficiently to hold the flap adequately in place.

After this, the shoe may be released from the clamp illustrated in Fig. 5 and the side margins 64 of the covering flap 12 trimmed, for example, flush with the sides 36 of the heel as by means of the knife 66. If a carrier 40 has been used, this trimming operation will remove simultaneously the projecting portions of the adhesive carrier 40 including the uncoated margins 44 thereof. Such an adhesive carrier will be of material sufficiently thin so that it will be practically invisible in the completed shoe. After this the top lift (not shown) may be attached and any other finishing operations carried out.

While the method has been described as involving the use of a clamping mechanism, such as is shown in Fig. 5 it will be found in certain cases that it may be usefully employed to secure the flap to the heel breast in shoes where the flap is merely rubbed and wiped into position on the breast and the clamping is eliminated.

Having thus described our invention, what we claim as new and desire to secure by Letters Patent of the United States is:

1. That improvement in methods of making shoes in which a covering flap is provided upon the sole of the shoe for the breast of the heel attached to said shoe which consists in providing a film of dried glue between said flap and the breast of the heel, directing a jet of steam upon said film to bring it to a tacky condition, applying steam to the outer surface of the covering flap to temper it, and then laying the flap against the breast of the heel. 70

2. That improvement in the methods of making shoes which consists in splitting a flap from the sole of a shoe, coating the inner surface of said flap with glue, securing a heel to the shoe and coating its breast surface with glue, allowing said coatings to dry, applying steam to at least one of the coated surfaces to render it tacky, applying steam to the outer surface of the flap to 80 temper it, pressing together said flap and said heel, and resiliently clamping said flap to the heel to allow said adhesive to set. 85

3. That improvement in methods of making shoes which consists in splitting a flap from the sole of a shoe, securing a heel to the shoe over the split portion of the sole, from which the flap is removed, coating the inner surface of the flap with glue, allowing the coating to dry, tempering the flap 90 and rendering tacky the coating by the application of steam to the surface thereof, bonding said flap to the breast of the heel, and clamping said flap to the heel. 95

4. The method of attaching a cover to the breast of a heel which consists in reviving by the application of steam a dried adhesive coating on a carrier, interposing said carrier between the flap and the heel, and pressing said flap and carrier against the breast of 100 the heel. 105

5. The method of attaching a cover to the breast of a heel which consists in holding a carrier for adhesive having an uncoated margin by grasping said margin and presenting the carrier in the path of a jet of steam to revive a dried adhesive coating thereon, interposing said carrier between the flap and the heel, and laying the flap against the breast of the heel. 110

6. The method of attaching a cover to the breast of a heel which consists in reviving by the application of steam a dried adhesive coating on a carrier larger than the breast of the heel, interposing said carrier between the flap and the heel, laying the flap against the breast of the heel, and simultaneously trimming the side margins of the flap and the carrier. 120

7. The method of attaching a cover to the breast of a heel which consists in holding a carrier for adhesive having an uncoated margin and being larger than the breast of the heel by grasping its uncoated margin and presenting the carrier to a jet of steam to 125 130

revive a coating of dried adhesive thereon to bring the adhesive to a tacky condition, interposing said carrier between the flap and the heel, laying the flap against the breast of the heel, and thereafter simultaneously trimming the side margins of the flap and the carrier.

8. The method of attaching a cover to the breast of a heel which consists in reviving by the application of steam a dried adhesive coating on a carrier, applying steam to the outer surface of the cover to temper it, interposing said carrier between the flap and heel, and laying the flap against the breast of the heel.

9. The method of attaching a cover to the breast of a heel which consists in reviving by the application of steam a dried adhesive coating on a carrier larger than said heel breast, applying steam to the outer surface of the cover to temper it, placing the carrier between the flap and the heel, applying said flap to the heel, and thereafter trimming the side margins of the flap and the carrier.

25 10. The method of attaching a cover to the breast of a heel by means of a carrier provided with a dried, adhesive coating and adapted to be interposed between the flap and the heel, which consists in applying steam to the dried adhesive coating to revive it and render it tacky and to the outer surface of the cover to temper it, and laying the flap against the breast of the heel.

35 11. The method of attaching a cover to the breast of a heel by means of a carrier for adhesive having an uncoated margin which consists in grasping said margin and presenting the carrier to a solvent to revive a dried adhesive coating on the carrier, interposing said carrier between the flap and the heel, and laying the flap against the breast of the heel.

45 12. The method of attaching a cover to the breast of a heel by means of a carrier larger than the breast of the heel and having a dried adhesive coating which consists in reviving the adhesive coating on the carrier, interposing the carrier between the flap and the heel, laying the flap against the breast of the heel, and simultaneously trimming the side margins of the flap and the carrier.

In testimony whereof we have signed our names to this specification.

JOSEPH GOULDBOURN.
GEORGE HAZELTON.
